J. E. JENNINGS

MAST FOR HIGH TENSION ELECTRIC TRANSMISSION

Filed May 3, 1924

UNITED STATES PATENT OFFICE.

JOHN E. JENNINGS, OF NEW YORK, N. Y.

MAST FOR HIGH-TENSION ELECTRIC TRANSMISSION.

Application filed May 3, 1924. Serial No. 710,849.

To all whom it may concern:

Be it known that I, JOHN E. JENNINGS, a citizen of the United States, residing at New York, in the county of New York and State 5 of New York, have invented certain new and useful Improvements in a Mast for High-Tension Electric Transmission, of which the following is a full, clear, and exact description.

10 The invention relates to means for anchoring a mast in position, and the objects generally are: To provide anchoring means for the legs of a mast; to provide anchoring means for the legs of a mast equipped with 15 a supplemental means arranged on predetermined lines to meet certain strains to which the legs of the mast will be subjected; and to provide anchoring means for the legs of a mast adapted to be in position before 20 the mast is mounted thereon.

Drawings.

Figure 1 is a vertical elevation partly in section illustrating a mast mounted in accordance with the principles of the invention;

Figure 2, a section through the stub shaft on the line 2-2 of Figure 3 and illustrating the stub shaft anchoring means in top plan view;

Figure 3, a vertical section of the earth fill around the anchor which is shown in elevation;

Figure 4, a plan view of the grillage construction at the bottom of the anchoring means.

Description.

As shown, 10 designates a grill work mast 40 of the usual construction for supporting high tension electric wires, provided with the usual supporting insulators 11 disposed thereon. These masts are of the construction generally employed and need no particular reference, as it will be understood that they are of the usual base construction having the leg members 12, formed of angle steel bars.

The particular anchoring mechanism employed consists of a stub-shaft for each leg formed of an angle girder 13 extending upwardly from the grill work 14 at the base thereof, and at a slight inclination from the

vertical, which degree of inclination is predetermined in accordance with the particular disposition of the mast when in upright position. The grill work 14 comprises a rectangular framework consisting of channel side bars 15 and 16 having bolted or otherwise suitably secured thereto channel end 55 bars 17 and 18 and provided with transversely extending centrally disposed channel bars 19 and 20 between which is riveted a foot flange of the stub shaft beam 13. As best illustrated in Figure 3, the supplemental anchoring means employed consists of a plurality of channel bars, preferably four in number, 21, 22, 23 and 24, riveted or otherwise suitably secured at one end to a flange of the channel beam 13 and extending therefrom in downwardly inclined directions. Adjacent the free ends of each of the supplemental supporting bars referred to are riveted or otherwise suitably secured 60 cross brace bars 25, 26, 27 and 28 respectively, which are set at right angles relatively to the particular bars to which they are attached, and provide in effect barbs for effectively anchoring the supplemental supporting bars in the earth.

In operation, a post hole is first dug in the hard earth, generally indicated as at 29, and a stub shaft 13 and grill work 14 disposed therein with the grill work resting on the bottom of the excavation. In positioning the stub shaft, the supplemental supporting bars 21, 22, 23 and 24, with their respective cross bars, will be driven into the hard earth at the sides of the excavation, firmly anchoring the stub shafts in position at the proper degree of inclination. In applying the supplemental supporting bars the ends of the bars are driven in the walls of the excavation at an angle to bring the inner ends of the bars in position for alignment with rivet 85 holes in the stub shaft. When in position the inner ends of the bars are rigidly secured to the stub shaft. The loosened earth generally designated as at 30 and 31 is then filled into the hole and securely packed 90 around the stub shaft and anchoring bars. When in position, the upper edge of the stub shaft beam 13 will project sufficiently 100 to permit the disposition thereover of the leg beam 12 of the mast, which, when applied, is riveted to the upper end of the stub

shaft beam, as illustrated in Figure 3, and the mast is secured in position.

Claims.

- 5 1. Mast supporting means comprising a base member adapted to be disposed at the bottom of an excavation, a stub shaft extending upwardly therefrom, laterally projecting supplemental anchoring members rigidly secured at one end to said stub shaft and adapted to be engaged at the opposite end in the walls of the excavation, anchoring members disposed adjacent the ends of said supplemental anchoring means, and means for attaching a mast leg to the upper end of said stub shaft.
- 10 2. Mast supporting means comprising a base member adapted to be disposed at the bottom of an excavation, a stub shaft extending upwardly therefrom and at an angle to the vertical, downwardly inclined laterally extending bars rigidly fastened at one end to said stub shaft and adapted to engage the walls of the excavation, anchoring members carried on said bars adjacent the ends at right angles thereto, and means for securing a mast leg to the upper end of said stub shaft.
- 15 3. Anchoring means for a mast comprising a base adapted to be disposed at the bottom of an excavation, a beam secured to said base and extending upwardly therefrom at an inclination to the vertical, downwardly inclined bars rigidly secured to said beam and projecting laterally therefrom to en-

gage in the walls of the excavation, cross braces rigidly secured on said bars inwardly of the ends thereof, and means for securing the mast leg to the upper end of said beam.

4. Mast supporting means comprising a grill work formed of channeled metal bars adapted to be disposed at the bottom of an excavation, a channeled beam extending upwardly therefrom and secured at its lower end to said grill work, channeled metal bars secured to said beam adjacent its upper end and projecting laterally therefrom at opposite sides thereof for engagement with the walls of the excavation, cross braces riveted to said bars adjacent the outer ends thereof, and means for securing a mast leg to the upper end of said beam.

5. Mast supporting means comprising a base grill work adapted to be horizontally disposed at the bottom of an excavation, a stub shaft having a foot extending therefrom, means carried by said grill work for securing said foot therebetween in attaching relation to said grill work, said stub shaft extending upwardly from said grill work at an angle, downwardly inclined laterally extending bars fastened each at one end to said stub shaft at right angled relation to one another with their free ends adapted for engagement in the walls of the excavation and anchoring members on the free ends of said bars and disposed at right angles thereto, and means for securing a mast leg to the upper end of said stub shaft.

JOHN E. JENNINGS.
